Primary Examiner — L. Martinez(74) *Attorney, Agent, or Firm* — Polson Intellectual Property Law, PC; Margaret Polson**CLAIM**

The ornamental design for a watch band with a reflective strip, as shown and described.

DESCRIPTION

The patent or application file contains at least one drawing executed in color. Copies of this patent or patent application publication with color drawing(s) will be provided by the Office upon request and payment of the necessary fee. FIG. 1 is a top, left side isometric view of a watch band with a reflective strip showing our new design.

FIG. 2 is a front side elevation view of FIG. 1.

FIG. 3 is a back side elevation view of FIG. 1.

FIG. 4 is a right side elevation view of FIG. 1.

FIG. 5 is a left side elevation view of FIG. 1.

FIG. 6 is a top plan view of FIG. 1; and,

FIG. 7 is a bottom plan view of FIG. 1.

1 Claim, 5 Drawing Sheets
(2 of 5 Drawing Sheet(s) Filed in Color)(56)
